UNITED STATES PATENT OFFICE

171,920

TEXTILE FABRIC

Allan Zimmerman, New York, N. Y.

Application August 6, 1953, Serial No. 26,301

Term of patent 3½ years

(Cl. D92—1)

To all whom it may concern:

Be it known that I, Allan Zimmerman, a citizen of the United States, residing at New York city, State of New York, have invented a new, original, and ornamental Design for Textile Fabric, of which the following is a specification, reference being had to the accompanying drawing, forming a part hereof.

The figure is a plan view of a textile fabric, showing my new design.

I claim:

The ornamental design for a textile fabric, as shown.
